(57) **CLAIM**

The ornamental design for a hair dryer, as shown and described.

DESCRIPTION

FIG. 1 is a perspective view of a hair dryer showing our new design;

FIG. 2 is a front view thereof;

FIG. 3 is a rear view thereof;

FIG. 4 is a left sideview thereof;

FIG. 5 is a right side view thereof;

FIG. 6 is a top view thereof;

FIG. 7 is another perspective view thereof in used state; and, FIG. 8 is a partially enlarged view indicating the circled area "8" in FIG. 7.

The dashed broken lines depict portions of the hair dryer in which the design is embodied that form no part of the claimed design.

The dot-dashed broken lines indicating an enlargement portion of the design form no part of the claimed design.
